UNITED STATES PATENT OFFICE

142,227

DESIGN FOR A GAS ANALYZING APPARATUS

Alexander I. Newman, River Forest, Ill., assignor
to Precision Scientific Co., Chicago, Ill., a cor-
poration of Illinois

Application June 22, 1944, Serial No. 114,127

Term of patent 14 years

(Cl. D16—2)

To all whom it may concern:

Be it known that I, Alexander I. Newman, a citizen of the United States, residing in the Village of River Forest, County of Cook, and State of Illinois, have invented a new, original, and ornamental Design for a Gas Analyzing Apparatus, of which the following is a specification, reference being had to the accompanying drawing, forming part thereof.

Figure 1 is a top plan view of a gas analyzing apparatus embodying my new design, and

Fig. 2 is a front perspective view of the apparatus.

I claim:

The ornamental design for a gas analyzing apparatus, substantially as shown.

ALEXANDER I. NEWMAN.
